UNITED STATES PATENT OFFICE.

FRANK RUSH WAINWRIGHT, OF JERSEY CITY, NEW JERSEY.

SCALE ATTACHMENT.

Application filed October 7, 1921. Serial No. 506,021.

To all whom it may concern:

Be it known that I, FRANK RUSH WAINWRIGHT, a citizen of the United States, and resident of Jersey City, in the county of Hudson and State of New Jersey, have invented a new and Improved Scale Attachment, of which the following is a full, clear, and exact description.

My invention relates to a scale attachment, and aims to provide a device of this character, more particularly in the nature of a display device which may serve as an advertising medium, or any other suitable purpose.

More particularly it is an object of my invention to provide an attachment for any conventional type of scale which may be associated with this scale, subsequent to its manufacture, or be applied at the time of its manufacture and which will be actuated by the movement of the scale mechanism in such a manner that the person using the scale will immediately notice the display device and the advertising or other matter placed thereon.

It is another object of my invention to construct a device of the character stated which shall be capable of being manufactured at an extremely nominal figure and in which the parts will be relatively simple, so that the danger of their becoming broken or disarranged is reduced to a minimum, aside from the fact that the attachment shall be of such a character as not to interfere in the slightest with the correct operation of the scale.

Still further objects of this invention will become apparent from the annexed specification taken in connection with the drawings, which latter illustrate one practical embodiment of the same, and in which;

Figure 1 is a front elevation of a scale with my improved attachment associated therewith, the said scale having a portion of its casing broken away to disclose the underlying structure.

Figure 2 is a view similar to Figure 1 but showing the parts in a slightly different position, and

Figure 3 is a transverse sectional view taken along the line 3-3 and in the direction of the arrows indicated in Figure 1.

In these views it will be seen that I have illustrated a conventional form of platform scale the base of which is indicated by the reference numeral 5, the reference numeral

6 the platform which by means of conventional mechanism 7 serves to operate an indicator 8, which latter designates the weight placed upon the platform 6 by means of a conventional dial 9 with which it co-operates.

The foregoing is entirely conventional construction, and I wish it understood that my attachment is susceptible of association with any desired type of scale. Also in the embodiment illustrated I have shown merely one type of indicator, hereinafter more fully described, and which is susceptible of being used in the connection stated, but it will be readily appreciated that any desirable type of indicator may be used to advantage with any type of scale.

Referring to this attachment it will be seen that in the embodiment illustrated the same includes a rotatable drum 10 upon which a strip of suitable material 11 is coiled, the outer end of this strip of material being preferably weighted as at 12 and extending past a window in the casing 14. A suitable operating mechanism for synchronizing the movement of this drum with the movement of the platform 6 is provided by simply utilizing an operating arm 14' which has one of its ends connected to the mechanism 7, its opposite end carrying a serrated bar 15, which meshes with a gear 16 fixedly secured to the drum 10.

Thus upon a person occupying the platform 6 the operating mechanism 7 will primarily be actuated to cause a corresponding movement on the part of the indicator 8, and this movement will also be transmitted to the drum 10 resulting in an unrolling of the strip or curtain 11, and a displaying of the writing upon this member through the window 13.

It is to be noted in this connection that although the characters may be of any desired type of advertising or otherwise, that the strip of material 11 in the embodiment illustrated is particularly adapted to bear advertising matter somewhat of the following nature. Assuming that the weight illustrated would indicate a person is emaciated, a slogan such as "Drink milk" would appear through the window, while various other foods or beverages would be indicated the further the platform 6 was depressed.

Thus all of the objects set forth in the preamble of this specification have been accomplished, and it will also be understood

that numerous modifications of structure might readily be resorted to without departing from the spirit of my invention, which I claim as:

- 5 1. The combination with a weighing scale, of an attachment therefor comprising a casing having a window opening, a rotary drum in said casing, a strip having indicia inscribed thereon secured at one edge of and wound upon said drum, a weight at the free lower edge of said strip, and means operable upon movement of the actuating mechanism of the weight indicating element for rotating said drum in a direction to effect the unwinding of the strip for the display of certain of the advertising indicia through the window opening.
- 10 2. The combination with a weighing scale, of an advertising device comprising a casing having a window opening, a rotary drum in said casing, a strip having advertising indicia inscribed thereon secured at one edge of and wound upon said drum, a weight at the free lower edge of said strip, means operable upon movement of the actuating
- 15 3. The combination with a weighing scale, of an advertising device comprising a casing having a window opening, a rotary drum in said casing, a strip having advertising indicia inscribed thereon secured at one edge of and wound upon said drum, a weight at the free lower edge of said strip, and means operable upon movement of the actuating mechanism for the weight indicating element for rotating said drum respectively in opposite directions to cause the unwinding of the strip for displaying certain of the advertising indicia through the window opening and subsequently the winding of the strip upon the return movement of the actuating mechanism to normal position.

FRANK RUSH WAINWRIGHT.
